F. W. OEHRLIE.

MACHINE FOR MAKING ORNAMENTAL ROPE OR CORD.

APPLICATION FILED JULY 20, 1918.

1,310,401.

Patented July 15, 1919.

UNITED STATES PATENT OFFICE.

FRANKLIN W. OEHRL, OF PHILADELPHIA, PENNSYLVANIA.

MACHINE FOR MAKING ORNAMENTAL ROPE OR CORD.

1,310,401.

Specification of Letters Patent. Patented July 15, 1919.

Substitute renewal for application Serial No. 65,639, renewed December 7, 1915. This application filed July 20, 1918. Serial No. 245,907.

To all whom it may concern:

Be it known that I, FRANKLIN W. OEHRL, a citizen of the United States, and a resident of Philadelphia, in the county of 5 Philadelphia and State of Pennsylvania, have invented an Improvement in Machines for Making Ornamental Rope or Cord, of which the following is a specification.

My invention relates to machines employed 10 in the manufacture of ornamental ropes or cords, and it has for one purpose and object the simplification of the construction of such machines.

Although relating generally to machines 15 of the character specified, the specific object of the construction illustrated herein is to provide a convenient and effective form of means for holding the former in stationary position, around which former the ornamental loop threads are coiled, and also for assisting in the removal of the said coiled 20 ornamental threads from said former.

One form of a convenient embodiment of 25 a construction adapted for these purposes is illustrated in the accompanying drawings, but it will be understood that changes in the details of construction may be made within the scope of the claims without departing from my invention.

30 In the drawings:—

Figure 1 is a view partly in side elevation and partly in vertical longitudinal section;

Fig. 2 is an end elevation looking toward the left in Fig. 1;

35 Fig. 3 is a perspective view of the former separated from the rest of the mechanism;

Fig. 4 is a longitudinal sectional view of the inner thread guide and the former secured thereto; and

40 Fig. 5 is a view showing a modification of means for securing the former in position.

In order that the drawings may be as simple as possible, consistent with a clear showing of my invention, I have omitted 45 therefrom the parts of the machine which are not essential to the illustration and proper understanding of my invention.

For instance, I have omitted the rack upon which the spools are supported from which the ornamental strands or threads which enter into the construction of the rope are supplied, and I have also omitted the twister device which is of known construction and which operates in a known manner.

In the drawings, 1 designates the frame of 55 the machine, and 2, 3 and 4 designate uprights or standards thereon.

The standards 3 are provided with bearings 5 in which the revoluble member 6 is mounted. The member 6 is provided with 60 flying arms 7 and 8, two of such arms being provided for the purpose of maintaining the balance of the said revoluble member 6.

10 designates the spool from which the 65 inner binding thread 11 is supplied. The said spool preferably is secured upon a sleeve 12 which is loosely and revolubly mounted upon the cylindrical hollow bearing 13 which is firmly secured in an opening 14 in the upright 2 by means of a binding screw 15.

The binding thread 11 passes from the spool 10 through loop guides 16 upon the arm 7 and thence through an opening 20 in 75 the guide member 21, which opening alines with the opening 22 in the former 23 secured to the member 21. The member 21 is loosely held in an opening 24 in the plugs or blocks 25 and 26 secured by means of 80 screws 27 (only two of which are shown) in the revoluble member 6.

The guide member 21 is held in the said plug or blocks 25 and 26 by means of ball bearings 28 which fit partly in a semi-circular groove 29 around the said guide member and in a semi-circular groove 30 in the opening or hole 24 through the said plugs or blocks 25 and 26 at the line of contact between the said blocks. The said blocks may 90 be secured together by screws (not shown) if desired.

23 designates a former which is of flat tongue like shape which is detachably se-

cured by means of a binding screw 32 to the projecting end of the guide member 21. For the purpose of holding the said former against rotation (and in the construction 5 illustrated the guide member 21 also being held against rotation by the same means,) I have provided holding rollers 35 and 36 between which the tongue-like former projects. The said rollers are journaled in 10 bearings 37 and 38 mounted in slots 39 upon the upright members 4.

The bearings 38 are connected to the lower 15 ends of rods 40 which are guided in holes or openings through the plates 41. Springs 42 are located between the said plates 41 and the said bearings 38 whereby the roller 36 is held downwardly by a spring action.

A driving gear 45 is provided upon the 20 shaft of one of the said rollers which gear is itself driven from any source of power not shown. Each of the shafts of the said rollers 35 and 36 is provided with gear wheels 46 and 47 which intermesh whereby the driving of one of said shafts causes revolution 25 of both of the said rollers 35 and 36. Such revolution is for a purpose to be hereinafter referred to.

By reason of the fact that the tongue-like former 23 is flattened, as indicated, it is obvious 30 that by locating the end thereof between the said rollers, the latter hold the same against revolution notwithstanding the revolution of the member 6.

The strands or threads from which the 35 ornamental loops are formed are taken from spools supported upon racks or in any other suitable manner (not shown) and extend through the guide members 50. The rear end of the said guide member 50 is connected 40 to a horizontal pivot 51 which is in turn supported upon the upper end of the vertical, pivoted member 52 which is supported in the tubular bearing 53 which bearing is secured as indicated at 54 to a flange upon the 45 lower end of the upright 2. The vertical pivoted member 52 is held in the said bearing by means of a pin 55.

The intersection of the axes of the pivots 51 and 52 is at a point co-axial with the axis 50 of the revolute member 6, and from the said point the member 50 extends at an angle to the axis of the said revolute member to a point beyond the forward end of the latter.

The length of the projection of the guide 55 tube 50 beyond the revolute member 6 is such that its revolution with the revolute member 6 causes the winding or coiling of the loop strands or threads around the tongue-like former 23 as is clearly indicated 60 in Fig. 1 of the drawings.

The outside binding thread 60 which contacts with the inner binding thread 11 may be of any suitable material and is supplied from a spool not shown and extends around

the roller 35 being positioned in a groove 61 65 therein.

The forward ends of the binding threads 11 and 60 are connected to a twister (not shown) which is caused to travel away from the said former and at the same time twist 70 the said binding threads together in a known manner and thereby bind one side of the walls of the coiled ornamental threads or strands between the said binding threads, the said coils extending laterally from the 75 said threads and therearound in the form of a continuous spiral.

The opposite edges of the flattened former are inclined so that the tendency is for the threads coiled upon said former to 80 slip therefrom, and the rotation of the rollers 35 and 36 assists in causing the coiled threads to be fed forward and off of the said tongue-like former 23 and by reason of the fact that the upper one of the rolls is spring-pressed but is vertically movable the said rollers may be separated so as to accommodate and co-operate with formers of different thicknesses and also to permit the use of thicker threads or strands to form the ornamental loops of a greater number of strands in which case the thickness of the loop strands wound around the former would be greater.

In Fig. 5 I have shown a modification of 95 the means for securing the inner thread guide and former to the revolute member 6.

In said Fig. 5, 65 designates a plug having a central opening 66 therein through which the guide member 67 is inserted. The former 23 is of the same construction and is supported upon the member 67 in the same manner as illustrated in previous figures. The member 67 is loose in the opening 66 and is held therein by means of a shoulder 105 68 formed thereon. To the inner end of the member 67 I have secured a sleeve 70 which prevents the removal of the member 67 from the opening 66 without first removing the said sleeve.

The arrangement illustrated in Fig. 5 is economical and is at the same time efficient.

Having thus explained the nature of my said invention and described some of the ways of making and using the same although 115 without attempting to set forth all of the forms in which it may be made or all the modes of its use, what I claim is:—

1. In a machine for making ornamental rope or cord, the combination of a revolute 120 member, a former supported upon the said revolute member, and means separate from and independent of said revolute member for holding the said former in stationary position, means for supporting an outer binding thread in operative relation to said former, an inner binding thread extending through said former and being supported 125

- and guided thereby, a supporting and guiding device for loop strands or threads, which device is carried upon said revolute member, the revolution of the latter causing 65
 5 revolution of the said device for coiling or winding the loop threads or strands around the said former and around a portion of the said inner binding thread, a revolute means for supporting a supply of the inner binding 70
 10 thread, and means for drawing off the said inner binding thread and thereby causing the said revolute inner binding thread supporting means to revolve in the same direction as the supporting and guiding device 75
 15 for the loop threads or strands.
2. In a machine for making ornamental rope or cord, the combination of a revolute member, a stationary former supported at the inner end of said revolute member and 80
 20 coaxially therewith, means independent of the said revolute member and separate therefrom for holding the said former in stationary position, a constituent part of the said means acting as a support and 85
 25 guide for an outer binding thread, an inner binding thread extending through and being guided by the said former, a guiding device for the loop threads or strands, which device is supported upon the said revolute 90
 30 member, and which terminates at a point laterally of the said former, whereby revolution of the said revolute member causes revolution of the said device around the said former and consequently the winding or coiling of the said loop threads therearound and 95
 35 around the said inner binding thread, a revolute spool supported coaxially with the said revolute member through which spool the said loop threads or strands extend, and 100
 40 means for drawing off the inner binding thread and thereby causing revolution of the said spool in the same direction as that of the revolution of the said revolute member, the inner binding thread at its point 105
 45 of separation from the said spool being held in constant relation to the said revolute member and to the said loop thread or strand guiding device.
3. In a machine for making ornamental 110
 50 rope or cord, the combination of a revolute member, a former supported upon the said revolute member, rollers between which the forward end of the said former extends, such rollers holding the former stationary, 115
 55 one of the said rollers supporting and guiding an outer binding thread and the said former supporting and guiding an inner binding thread, a supporting and guiding device for the loop threads or 120
 60 strands of the rope, which device terminates at a point laterally of the said former and which device is supported upon the said revolute member, the revolution of which causes the coiling or winding of the said 125
 65 loop threads or strands around the said former, and means for causing revolution of the said rollers for feeding the said coiled threads or strands from the said former.
4. In a machine for making ornamental rope or cord, the combination of a revolute member, a flattened former supported thereon, rollers for holding the said former stationary between which the said former extends, and one of the rollers being supported in spring pressed bearings, whereby the distance between the said rollers may be varied, and one of the said rollers supporting and guiding an outer binding thread and the said former supporting and guiding an inner binding thread, a device for supporting and guiding the loop threads or strands, which device is supported upon the said revolute member and terminates at a point laterally of the said former, and the revolution of the said revolute member causing 80

5. In a machine for making ornamental rope or cord, the combination of a revolute member, a former supported thereon and in axial alignment therewith, means independent of the said revolute member for holding the said former against rotation, and a thread or strand guiding member also supported upon the said revolute member and being in operative relation to said former.
6. In a machine for making ornamental rope or cord, the combination of a revolute member, a former supported thereon and being in axial alignment therewith, means including a spring pressed member for holding the said former against rotation, and a thread or strand guiding member also supported upon the said revolute member, one end of the said thread guiding member being situated adjacent to and laterally of the said former.
7. In a machine for making ornamental rope or cord, the combination of a former, said former having an axial opening extending therethrough, means for supporting 115

said former having an axial opening extending therethrough, means for supporting said former, means for supporting a binding thread, said means having an opening in alignment with the opening through said former, the said binding thread passing through the aligned openings, means for supporting another binding thread laterally of and in operative relation to said former,

means for coiling threads around said former and revoluble means in engagement with the threads upon said former to assist in removing the same therefrom.

In testimony that I claim the foregoing as my invention, I have heretunto signed my name this eighteenth day of July, A. D., 1918.

FRANKLIN W. OEHRLER.

Copies of this patent may be obtained for five cents each, by addressing the "Commissioner of Patents, Washington, D. C."
